FIG. 1 is a perspective view taken from the right front side of a combined handle and lock housing embodying my new design;

FIG. 2 is a left side view of the embodiment shown in FIG. 1;

FIG. 3 is a front view of the embodiment shown in FIG. 1;

FIG. 4 is a right side view of the embodiment shown in FIG. 1;

FIG. 5 is a back view of the embodiment shown in FIG. 1;

FIG. 6 is a top view on an enlarged scale of the embodiment as shown in FIG. 4; and

FIG. 7 is a partial right side view on a greatly enlarged scale of the embodiment shown in FIG. 1.

The shading employed does not connote actual appearance, but is an expedient to best illustrate shape.

I claim:

The ornamental design for a combined handle and lock housing, as shown and described.
